UNITED STATES PATENT OFFICE.

HARRY O. DAVIDSON AND WILLIAM P. CUNNINGHAM, OF CLEVELAND, OHIO.

CONCRETE-FORM.

1,249,039.

Specification of Letters Patent. Patented Dec. 4, 1917.

Application filed March 14, 1917. Serial No. 154,684.

To all whom it may concern:

Be it known that we, (1) HARRY O. DAVIDSON, and (2) WILLIAM P. CUNNINGHAM, citizens of the United States, residing at Cleveland, in the county of Cuyahoga and State of Ohio, have invented a certain new and useful Improvement in Concrete-Forms, of which the following is a full, clear, and exact description, reference being had to the accompanying drawings.

This invention relates to concrete forms, and more particularly to a device for clamping form plates to the beams or girders of a building frame or structure.

The objects of the invention are the provision of a device of the aforesaid character which may be readily connected to the flanges of an I beam or the like, for suspension therebeneath, and adjustable to fit beams of varying widths within reasonable limits; which involves a clamping element for coöperation with the edge portions of adjoining form plates for holding them in firm contact with the beam and serving, at the same time, to draw the plates into proper position with respect to the sides of the beam; which includes means, positive of action yet very convenient of manipulation, for moving the clamping element relative to the hanger, and which means is durable, is not easy to get out of order, and serves to lock the parts in clamping position; the provision of a device of the above character wherein the elements are permanently connected, thus avoiding the possibility of loss of parts; and which can be quickly and easily removed from the beam.

In the drawing accompanying and forming a part hereof we have shown our invention incorporated in what are known as "dome ceiling" forms associated with the horizontal beams of a structural steel frame. Figure 1 is a fragmentary vertical section through the structure on a plane transverse to the ceiling beams and shows our improved form in place; Fig. 2 is a section on the line 2—2 of Fig. 1, looking in the direction of the arrows; Fig. 3 is an enlarged sectional detail through one of the clamping devices and the adjacent parts of the form plates and I beam; and Fig. 4 shows the various elements of the clamping device in separated condition.

Describing the invention by the use of reference characters, 1 represents the I beams of a structural steel frame to the underneath surface of which are clamped, by the use of our improved clamping devices; the edge portions of the form plates 2, the plates being shown herein as of a shape to produce the so-called "dome ceiling" effect. Attention is called to the formation of the edge portions of the plates where the plates curve downward substantially in contact with the edges of the I beam flanges and then extend horizontally therebeneath toward the center of the beam, as shown at 3, where their extreme edge portions are then inclined downward and inward, as shown at 4.

At suitable distances along their edges, the plates are provided with notches 5 for the passage of the hooked ends 10 and opposed hooked fingers 10^a of the hangers 11. Each hanger comprises two metal straps 12 that have their lower ends connected by a ring 15 and extend upward alongside each other to a point below the plane of the edge portions 4 of the form plates, where they are turned outward in opposite directions beneath such edge portions and then upward beneath the side edges of the beam, the one terminating in the previously mentioned hooked finger 10, and the other being perforated for the reception of a bolt 16 by means of which, and the thumb nut 17, the hooked finger 10^a is clamped to the upturned end of the adjacent strap 12. Just below their horizontal portions the straps are provided with alining holes for the passage of the bolt 18, having applied to it the nut 19, and through which the straps may be adjusted toward and from each other to fit beams of various widths.

A U-shaped clamping element 20, which is shown as made of sheet metal and of channel formation in cross section, has the web of its central portion provided with an opening 21 through which the vertical portions of the straps 12 pass, while the webs of its side branches are notched downward from their upper ends at 22 for the passage of the upper ends of the straps. The upper ends of the clamping element are arranged for contact with the portions 3 of the form plates, and the corners of the side

flanges of the clamping member are shown as inclined to correspond substantially to the inclination of the portions 4 of the plates.

5. Aligning slots 25 are formed in the straps 12 near their lower ends for the reception of a wedge 26 which engages, at its lower edge, the bottom of said slots, and at its upper edge, the underneath surface of the 10 clamping element. A rivet 27 extends through the smaller end of the wedge for preventing its complete withdrawal from the slots.

In assembling the form, the hangers are 15 distributed along the I beams according to the location of the notches 5 of the plates and are attached by placing the hooked fingers 10 over one flange and then loosening the thumb nuts 17 until the hooked fingers 20 10^a may be swung over the other, after which the nuts 17 may be tightened to clamp the fingers against the adjacent parts of the straps 12, it being understood that the hangers are adjusted through the bolts 18 to 25 snugly fit the I beam. With the edges of the plates within the embrace of the clamping elements, the wedges 26 are forced or driven into the openings 25 to elevate the clamping elements. The corners of the side 30 flanges of the clamping elements engage the inclined edge portions 4 of the plates and draw them together to bring the adjacent angles of the plates into close proximity to or in engagement with the opposed edges of 35 the I beam, the ends of the clamping elements finally engaging the portions 3 of the plates and holding them in firm contact with the beam. When it is desired to remove the plates, the wedges 26 are driven in a direction to lower the clamping elements; and the hangers may be removed by loosening the nut 17 and disengaging the hook finger 10^a, and after that the hook finger 10, from the beam. At the right hand side of 40 Fig. 1 and the left hand side of Fig. 2, the clamps are shown as loosened, while the other clamps of the respective views are shown in effective condition.

Having thus described our invention, 50 what we claim is:

1. Apparatus designed for use with beams having opposed supporting portions, said apparatus comprising a hanger having hooks for engagement with said supporting portions, a form plate for engagement with the face of the beam, a clamping element movable with respect to the hanger for engagement with the plate, and means carried by the hanger for so moving said element.

60 2. Apparatus designed for use with beams having opposed supporting portions, said apparatus comprising a hanger having hooks for engaging said supporting portions, a plate applied to the face of the beam 65 and cut away for the accommodation of the

hanger, a clamping element movable on the hanger into contact with the plate, and means carried by the hanger for so moving said element.

3. Apparatus designed for use with beams 70 having opposed supporting portions, said apparatus comprising a hanger having parts for engagement with said supporting portions thereby to suspend the hanger below a beam, a plate for application to the under 75 side of the beam, a clamping element movable with respect to the hanger into contact with the plate, the hanger having an abutment spaced from a portion of said element, and a wedge insertible between said abutment and the clamping element.

4. Apparatus designed for use with beams 80 having opposed supporting portions, said apparatus comprising a hanger having parts for engagement with said supporting portions 85 thereby to suspend the hanger below a beam, opposed plates having edge portions for engagement with the underside of the beam, a clamping element movable with respect to the hanger into contact with the 90 edge portions of the plates, and means carried by the hanger for so moving said element.

5. Apparatus designed for use with beams 95 having opposed supporting portions, said apparatus comprising a hanger having parts for engagement with said supporting portions thereby to suspend the hanger below a beam, opposed plates having portions for engagement with the underneath surface of the 100 beam adjacent each side thereof and having edge portions which converge downward from the beam, a clamping element movable with respect to the hanger to present parts thereof into engagement with the edge and 105 adjacent portions of said plates, and means carried by the hanger for so moving the clamping elements.

6. Apparatus designed for use with beams 110 having opposed supporting portions, said apparatus comprising a hanger having parts for engagement with said supporting portions thereby to suspend the hanger below a beam, opposed plates having portions for engagement with the underneath surface of 115 the beam, the adjacent edges whereof converge downwardly from the beam, a U-shaped clamping element movable vertically of the hanger to engage its ends with the adjacent portions and edges of the afore- 120 said plates, the hanger having an abutment opposed to the bottom of the clamping element, and a wedge insertible between the abutment and the bottom of said element.

7. Apparatus designed for use with beams 125 having opposed supporting portions, said apparatus comprising a hanger having parts for engagement with said supporting portions thereby to suspend the hanger below a beam, opposed plates extending downward 130

along and then beneath each side of the beam, the adjacent edges of the opposed plates converging downward from the beam, the plates being notched for the accommodation of the hanger, a U-shaped clamping element carried by the hanger the ends whereof are arranged to engage the edges of the plates, the hanger having a wedge receiving opening below the clamping element, 10 and a wedge within said opening.

8. Apparatus designed for use with beams having opposed supporting portions, said apparatus consisting of a hanger comprising straps having their lower ends connected and extending upward alongside each other and then outward in opposite directions beneath the beam with their upper ends provided with hooks for engagement with the aforesaid supporting portions of a beam, opposed plates having portions extending beneath the opposite sides of the beam, the adjacent edges whereof converge downwardly from the beam, the plates being notched for the accommodation of the hanger, a U-shaped element having a central aperture for the passage of the lower portion of the hanger and having notches in its opposed branches for the passage of the outturned portions of the hanger, the ends of the member being arranged for engagement with the adjacent portions of the opposed plates, the hanger being provided with a wedge receiving opening in the vicinity of the central portion of the clamping element, and a wedge within said opening.

9. Apparatus designed for use with beams having opposed supporting portions, said apparatus consisting of a hanger comprising straps having their lower ends connected and extending upward alongside each other and then outward in opposite directions beneath the beam with their upper ends provided with hooks for engagement with the aforesaid supporting portions of a beam, means adjustably connecting the upper ends of the straps, opposed plates having portions extending beneath the opposite sides of the beam, the adjacent edges whereof converge downwardly from the beam, the plates being notched for the accommodation of the hanger, a U-shaped clamping element having a central aperture for the passage of the lower portion of the hanger and having notches in its opposed branches for the passage of the outturned portions of the hanger, the ends of the member being arranged for engagement with the adjacent portions of the opposed plates, the hanger being provided with a wedge receiving opening in the vicinity of the central portion of the clamping element, and a wedge within said opening.

10. Apparatus designed for use with beams having opposed supporting portions,

said apparatus consisting of a hanger having a horizontal portion adapted to extend transversely beneath the beam one end whereof is turned upward and inward over one of the aforesaid supporting portions of a beam, a hooked finger movably connected to the opposite end of the horizontal portion, a form plate extending beneath the beam for engagement with the underneath surface thereof, a clamping element movable with respect to the hanger into contact with the plate, and means carried by the hanger for so moving said element.

11. Apparatus designed for use with beams having opposed supporting portions, 80 said apparatus consisting of a hanger having a portion that is arranged to extend substantially horizontally beneath the beam the ends whereof are provided with hooks for engagement with the aforesaid supporting portions of a beam, the hanger having a vertical portion depending from substantially the center of the horizontal portion, opposed plates having portions extending beneath the beam the adjacent 90 sides of the beam the adjacent 90

ends converge downwardly, a U-shaped clamping element of channel formation in cross section having a central aperture for the reception of the central portion of the hanger and having the webs of its vertical branches notched downward from their upper ends for the passage of the horizontal portion of the hanger, the aforesaid plates being notched for the accommodation of the hanger and arranged for engagement by the ends of the clamping element, and means for moving the clamping element upward along the vertical portion of the hanger.

12. Apparatus designed for use with 105 beams having opposed supporting portions, said apparatus comprising a hanger having a portion that is arranged to extend substantially horizontally beneath the beam the ends whereof are provided with hooks for engagement with the aforesaid supporting portions of a beam, the hanger having a vertical portion depending from substantially the center of the horizontal portion, opposed plates having portions extending beneath the sides of the beam, the adjacent edges whereof converge downwardly, a U-shaped clamping element of channel formation in cross section having a central aperture for the reception of the central portion 115 of the hanger and having the webs of its vertical branches notched downward from their upper ends for the passage of the horizontal portions of the hanger, the aforesaid plates being notched for the accommodation of the hanger and arranged for engagement by the ends of the clamping element, the inner corners of the ends of the clamping element being beveled to correspond substantially to the convergence of 120 125 130
